UNITED STATES PATENT OFFICE.

ALFRED B. BOWDEN, OF BARRINGTON, ASSIGNOR TO MYRON T. KINYON, OF PAWTUCKET, AND CALEB B. PARKER, OF WARWICK, RHODE ISLAND.

STEAM-DISCHARGING APPARATUS FOR COOKING-STOVES.

SPECIFICATION forming part of Letters Patent No. 254,193, dated February 28, 1882.

Application filed December 16, 1881. (No model.)

To all whom it may concern:

Be it known that I, ALFRED B. BOWDEN, of Barrington, in the county of Bristol and State of Rhode Island, have made certain new and useful Improvements in Steam-Discharging Apparatus for Cooking Stoves or Ranges; and I do hereby declare that the following specification, taken in connection with the drawings, making a part of the same, is a full, clear, and exact description thereof.

Figure 1 is a side elevation, and Fig. 2 is a vertical section, of the apparatus embracing my invention. Fig. 3 is a horizontal section of the socket and valve.

15 The object of my invention is to carry off the steam, vapor, and odor arising from the cooking of food; and it consists in the device for that purpose hereinafter described.

Cooking stoves and ranges have in their top 20 plates two or more apertures for the reception of pots, kettles, or other culinary vessels used for holding articles to be cooked by the fire or heat therefrom. From such pots or vessels usually arises steam or vapor more or less charged with odor, which, unless properly conducted into a discharge-flue, escapes into the apartment, and sometimes finds its way over the house. My invention is designed to prevent the escape of such steam or vapor into 25 the apartment and discharge the same into the stove or range.

I am aware that the cover of a pot has been connected with the smoke-discharge pipe by a tube; and I make no claim to any such device.

35 In the drawings, A denotes a stove or range hole cover, having extending down from it a cup or socket, B. The socket B is provided with an opening, a, on one side below the cover, and a shoulder, b, arranged in and around it, and 40 receives a vertical pipe, C, the lower end of which rests upon said shoulder.

In order to make the cover available when the discharging apparatus is detached, it is necessary to provide some means for closing 45 the opening a. For this purpose I make the shoulder b of a separate piece, H, Fig. 3, leaving upon one side an opening, I, corresponding with the opening a in the socket. This separate shoulder H is capable of rotation

within the socket B, so that the opening a may 50 be closed or opened, as desired.

From the pipe C, at or near its middle, extends a pipe, D, provided with a conical mouth-piece, E, the pipe D opening into the said mouth-piece and the pipe C. Fitting into the pipe C 55 at its upper end is a separate joining-tube, T, within which, at its upper end, is inserted an elbowed pipe, F, also provided with a conical mouth-piece, G, which opens into the said elbowed pipe. 60

With the apparatus as described the conical mouth-pieces can be arranged over two vessels at once while they may be in use in or over two of the holes of a stove or range. The socket B may be attached to any part of the stove- 65 plate, whether it be the cover or division-pieces.

The operation of my invention will be as follows: As the steam or vapor arises it will be drawn in by the mouth-pieces and carried down through the stove-plate, escaping into the stove 70 through the opening a. When the device is removed the shoulder or valve H is rotated so as to close the opening a, as described. With this arrangement for closing the opening a the same cover may be used all the time, or 75 the socket may be attached to any part of the stove-plate.

What I claim as my invention, and desire to secure by Letters Patent, is—

1. The combination of the two mouth-pieces 80 E G and their discharge and joining pipes C, D, T, and F, and the socket plate or cover A, the whole constructed and arranged substantially as set forth.

2. The stove plate or cover A, provided with 85 the pipe-receiving socket B, having a lateral opening, and the pipe-sustaining shoulder, as set forth.

3. The stove plate or cover A, constructed 90 with a socket, B, and having in combination therewith a rotating shoulder or valve, H, for the purpose of opening and closing the opening a, as specified.

ALFRED B. BOWDEN.
